UNITED STATES PATENT OFFICE.

HARRY G. HECKMANN, OF BINGHAMTON, NEW YORK, ASSIGNOR TO THE CENTRAL FLATIRON MFG. CO., OF JOHNSON CITY, NEW YORK, A CORPORATION OF NEW YORK.

DESIGN FOR A GAS-HEATED FLAT-IRON.

51,859.

Specification for Design.

Patented Mar. 12, 1918.

Application filed December 18, 1916. Serial No. 137,731. Term of patent 7 years.

To all whom it may concern:

Be it known that I, HARRY G. HECKMANN, a citizen of the United States, residing at Binghamton, in the county of Broome and State of New York, have invented a new, original, and ornamental Design for a Gas-Heated Flat-Iron, of which the following is a specification, reference being had to the accompanying drawings, forming part thereof.

Figure 1 is a plan view of a flat-iron embodying this design; Fig. 2 is a side elevation thereof; Fig. 3 is a front elevation and Fig. 4 is a rear end elevation of the same.

This design comprises a body having general outlines which are rather oval in form, and extend from the point in pleasing curves.

The points of greatest height and width occur somewhat rearwardly of midway between the front and the rear ends, from which points the top and sides taper at gradually increasing rates toward the front and rear ends, the front end of the top being curved downwardly and rounded over, as shown, so as to present a particularly pleasing appearance.

The bottom is substantially flat but inclined somewhat upwardly at the front and rear ends.

In plan view, the body presents the appearance of an ova-lateral straight base triangle, a number of openings are provided near the base of each side wall, and a slot is provided near the upper part of each side wall along the greater part of the length thereof, the upper and lower walls of said slot being substantially parallel with the top and base outlines of said body respectively.

A curved tube extends from the rear end of the body and a handle is supported above the top of the body by means of a curved strap, the curves of said tube and strap being so formed as to pleasingly harmonize with the curved outlines of the body.

What I claim and desire to secure by Letters Patent of the United States is:—

The ornamental design for a gas heated flat-iron substantially as shown and described.

H. G. HECKMANN.
